UNITED STATES PATENT OFFICE.

JOHN O. NEIKIRK, OF LOMBARD, ILLINOIS, ASSIGNOR TO RODGER BALLAST CAR COMPANY, OF CHICAGO, ILLINOIS, A CORPORATION OF MAINE.

CAR CONSTRUCTION.

Application filed December 11, 1922. Serial No. 606,921.

To all whom it may concern:

Be it known that I, JOHN O. NEIKIRK, a citizen of the United States, residing at Lombard, in the county of Du Page and 5 State of Illinois, have invented certain new and useful Improvements in Car Constructions, of which the following is a specification.

The present invention relates to car construction.

More particularly the present invention relates to improvements in the type of car which is convertible from a flat car type to a hopper car type, or vice versa, doors 15 being provided in the bottom of the car which are adapted to occupy horizontal positions to form part of the flat bottom of the car to constitute a flat car, and which in another alternative position form sloping sides to constitute part of the hopper of a hopper car.

When the sides of the car are of corrugated construction, if special provision were not made, spaces would be left between the 25 corrugations and the doors when said doors are in position to form sloping sides of the hopper.

An object of the present invention is to provide car construction of the convertible 30 type in which the escape of lading along the inside of the corrugated side walls is prevented.

A further object is to provide a simple 35 and sturdy attachment for cars of the convertible type having corrugated side walls which will co-operate with the doors such as referred to above in a manner to prevent the escape of dumpable material to a position out of communication with the hopper.

40 A further object is to provide improved construction of convertible car for preventing the lodging of dumpable material between the corrugated sides of such a car and the doors.

45 Further objects will appear as the description proceeds.

Referring to the drawings—

Figure 1 is a transverse sectional view of 50 a convertible railway car illustrating the present invention; and

Figure 2 is a fragmentary view in section illustrating, on an enlarged scale, part of the construction shown in Figure 1.

The numerals 10—10 represent the 55 corrugated side walls of a railway car, while

the numerals 11—11 indicate bottom walls. The numeral 12 indicates a fixed inclined side of a hopper, and the numeral 12' indicates a swinging side which is hinged along its longitudinal axis and which may be 60 controlled in any preferred way for closing said hopper or for permitting the dumping of the material in said hopper. Hinged about the axes 13—13 are the doors 14—14. One of said doors is shown in horizontal position in Figure 1 and the other of said doors is shown in inclined position.

Both doors 14—14 will occupy their horizontal positions when the car is used as a flat bottom car and will occupy their inclined positions when the car is to be used as a hopper car. Said doors will be of sufficient width to form a closure for the bottom of the car when in their horizontal positions. When in their inclined positions, 75 the doors form sloping sides of the hopper, whereby the hopper is self-cleaning. Though only one hopper door 12 and two hopper doors 14—14 are referred to herein, it will be understood that it is common 80 practice to provide multiples of these members along the desired length of the car.

On each of the sides 10—10 are mounted brackets 15. Each of said brackets 15—15 has a corrugated side 16 adapted to conform to the corrugations of its corresponding side wall 10. Each of said brackets is also provided with a flange 17 extending in a direction substantially parallel with the plane of its corresponding door 14 when 90 said bracket 15 is mounted in place and when its corresponding door is in its inclined hopper forming position.

The brackets 15—15 may be connected to the side walls 10—10 by rivets 18—18 or other preferred means. Each of the doors 14 may be supported when in inclined position by gusset plates 19—19, which provide inclined supporting walls as shown in Figure 1. These gusset plates may be secured to the side and floor of the car or to frame members thereof in any manner, such as by riveting. Said gusset plates not only support the doors 14—14 when said doors are in inclined position, but also serve as brace 100 members for strengthening the sides of the car. Each of the doors 14—14 may be provided at its outer edge with the Z bar 20, of which one flange 21 is secured to the edge of the door and the other flange 22 is adapted 110

to lie upon the sloping side 17 of bracket 15. Ordinarily both flanges 21 and 22 will have straight side edges.

It will be seen that the flanges 17-17 of the brackets 15-15 constitute shelves upon which the doors 14-14 may rest when in their inclined positions. Consequently, when the doors 14-14 are in their inclined positions, all of the lading is directed into the 10 hopper and none of said lading is permitted to pass between the edges of the door and the side walls of the car. Consequently, complete dumping of the car may be accomplished by opening the dump door 12'.

15 One embodiment of the present invention has been described in detail. Many modifications will occur to those skilled in the art. It is intended in this patent to cover all such modifications that fall within the 20 scope of the invention as defined by the appended claims.

I claim:

1. A convertible railway car comprising means providing hopper doors hinged along 25 longitudinal axes adapted in certain positions to cover said hopper and in other positions to form sloping walls for said hopper, said car having corrugated side walls, said side walls being provided with bracket 30 members conforming to the corrugations of said side walls and providing a flat bearing surface for the edges of said doors when said doors are in position to form sloping walls.

35 2. A railway car comprising means providing a hopper, doors hinged along longitudinal axes adapted in certain positions to cover said hopper and in other positions to form sloping walls for said hopper, said car having corrugated side walls, each of said 40 side walls being provided with a bracket conforming to the convolutions of said side

wall and having a shelf adapted to underlie one of said doors to prevent the passage of 45 dumpable material between the corresponding side wall and the corresponding door.

3. A railway car comprising doors hinged along longitudinal axes, said doors being provided with straight edges lying, when 50 said doors are in horizontal position, along lines longitudinally of the car, said doors being adapted to lie in inclined positions to form hopper walls, said car having corrugated side walls, said side walls being provided with bracket members having portions 55 conforming to the corrugations of said side walls and having portions adapted to be engaged by said doors to prevent the escape of dumpable material between said side walls and said doors.

4. A railway car having corrugated side walls and a bracket mounted upon each of 60 said side walls, each of said brackets having a corrugated portion conforming to the corrugations of said side walls and having a flange portion extending at an angle from the general plane of its corresponding side wall.

5. A railway car having corrugated side 65 walls, each of said side walls being provided with a shelf, said shelf having a corrugated portion conforming to the corrugations of its corresponding side wall.

6. A car of the class described, having corrugated side walls, longitudinally extending 70 doors adapted to be turned up to an inclined position against the said corrugated sides, and a plate secured to each of said sides providing a closure between said corrugated sides and said door when said door is in 75 80 said inclined position.

Signed at Chicago, Illinois, this 7th day of December, 1922.

JOHN O. NEIKIRK.
